SNOW RUNNER

Edwin A. Price, 1660 Trenton St., Denver, Colo. 80220

Filed Aug. 17, 1964, Ser. No. 81,305

Term of patent 14 years

(Cl. D34—15)

FIG. 1 is a perspective view of a snow runner embodying my new design;

FIG. 2 is a side elevation thereof, taken from the side opposite to that shown in FIG. 1;

FIG. 3 is a front elevation thereof;

FIG. 4 is a top plan view thereof; and

FIG. 5 is a side elevation corresponding to FIG. 2, wherein a generally circular spring beneath the seat is employed.

I claim:

The ornamental design for a snow runner, as shown and described.
